UNITED STATES PATENT OFFICE.

FERDINAND OTTO SCHMIDT, OF BERLIN, GERMANY.

SHUTTLE AND MECHANISM FOR OPERATING THE SAME.

SPECIFICATION forming part of Letters Patent No. 295,291, dated March 18, 1884.

Application filed June 6, 1883. (No model.) Patented in England November 13, 1882, No. 5,413; in France November 14, 1882, No. 152,026, and in Germany December 2, 1882, No. 23,556.

To all whom it may concern:

Be it known that I, FERDINAND OTTO SCHMIDT, of the city of Berlin, in the Kingdom of Prussia and German Empire, have invented certain new and useful Improvements in Shuttles and Mechanism for Operating the Same, of which the following is a specification.

My invention relates, in part, to improvements in the shuttle of a sewing-machine, and 10 in part to means for imparting a reciprocating oscillating motion to the said shuttle.

In the drawings, which serve to illustrate my invention, Figure 1 is a vertical mid-section of the shuttle, with its bobbin, on the plane 15 of line 1 1 in Figs. 3 and 4. Fig. 2 is a side elevation of the shuttle. Fig. 3 is a horizontal section on line 3 3 in Figs. 1 and 2. Fig. 4 is a plan of the shuttle, together with the inclosed bobbin and thread-guide. Fig. 5 is an elevation 20 of the thread-guide detached, showing the inside. Fig. 6 is an exterior elevation of the thread-guide, shown as if straightened out in order to better illustrate the parts. Fig. 7 is a plan of the thread-guide detached. Figs. 8 25 and 9 are respectively a plan and end view of the needle-plate. Fig. 10 is a view of the tension-regulating slide detached. Fig. 11 is a longitudinal section of the mechanism for actuating the shuttle; and Fig. 12 is a sectional 30 plan of same on line 12 12 in Fig. 11.

The shuttle A is of a cup form, and contains the part I call the "thread-guide" B, and the bobbin or thread-spool C. The shuttle is given an oscillatory reciprocating movement of more 35 than half a revolution by means that will be hereinafter described.

a is the point of the shuttle, which engages the loop of the thread at the needle, and b is a recess in the side of the shuttle, which engages 40 a driving-pin, w', on the shuttle-bearing disk y' (see Fig. 11) when the shuttle is in place.

In order that the proper access may be had to the interior of the shuttle at all times, no matter what may be its position, for threading, adjusting the tension, &c., I provide large 45 openings, c and d, in its sides, as indicated in Figs. 1, 2, and 3, and in order that the loop of thread may pass over the shuttle without chafing, I bevel and smooth off its corners, as 50 shown. In its axis the shuttle is provided

with a hollow spindle or arbor, e, to receive the tubular spindle f of the thread-guide B, and the spindle e is internally screw-threaded to receive a screw, g, which serves to keep the guide B from lifting up. The bobbin C is made 55 to slip onto the spindle of the thread-guide, on which it is free to rotate; but its movement of rotation is slightly restrained by a small leaf-spring, i, which rests in a recess in the tubular spindle f of the guide, and presses outward 60 elastically against the inner wall of the eye in bobbin C.

I will now describe the thread-guide B more particularly.

On the upper edge of the wall h of this guide 65 is a projection or shoulder, l, which engages a shoulder, m, on the needle-plate m' of the sewing-machine, as best indicated in Fig. 2, whereby the guide B is stopped from rotating with the shuttle when the latter is operated. The 70 guide B is rotatively mounted on the spindle e of the shuttle, but would move with the shuttle if not restrained in some manner.

In the wall h of the thread-guide is an opening, o, in which plays a tension-spring, n. This 75 spring is broadest at its free end n', and slightly overlaps the end of opening o. It plays freely outward toward the shuttle-wall. The thread from the bobbin passes out under the end of the spring n, and then through the holes p in 80 the walls h of the guide, to provide the necessary tension.

In order to vary the stiffness of the tension-spring n, and thus regulate the tension, I employ a slide, q. (Shown detached in Fig. 10.) 85 This slide consists of a bent plate arranged to embrace the wall h of the thread-guide B, and its two sides are connected by ties, which pass through the opening o above and below the spring n.

In order to prevent the slide q from being shifted accidentally, it is provided with a leaf-spring, r, the free end of which passes through an aperture in the slide and presses into slight notches (at r' in Fig. 6) in the face of the wall 95 h, in the manner of a light spring-pawl and ratchet. When the slide q is moved toward the free end of spring n, it acts to shorten the operative part of the spring and make it stiffer, thus increasing the tension. 100

In order to restrain the too free play of thread-guide on the spindle *e* of the shuttle, the guide may be provided with a light spring, *o'*, arranged to press outwardly against the inner 5 shuttle-wall.

I will now describe the mechanism for operating the shuttle, referring particularly to Figs. 11 and 12, premising that this mechanism is so constructed that a quarter-revolution of 10 the driving-shaft *s* will impart more than half a revolution to the shuttle-bearing disk *y'*.

On the lower end of the vertically-arranged driving-shaft *s* is fixed a crank, *t*, to which is coupled at *u* a connecting-rod, *v*. This rod 15 plays through and is guided in a rotatively-mounted guide-block, *w*, and bears on its end a rod, *x*, mounted to swing radially on a pin, *x'*, in *v*. The rod *x* plays through and is guided in a block, *y*, fixed to the vertically-mounted 20 spindle of the shuttle-bearing disk *y'*. This construction is such that the oscillation of crank *t* through a quarter of a revolution will impart an oscillation to the disk *y'* through more than half a revolution. The shuttle rests 25 loosely on disk *y'*, in order that the loop of the thread may pass freely around it; but it is compelled to move with the disk by reason of the engagement of the pin *w'* within the recess *b*.

I am aware that broadly it is not new to 30 arrange a thread-guide and bobbin in a cup-like shuttle; but I am not aware that a shuttle having all the characteristics of mine has ever before been proposed.

I am also aware that mechanism for converting 35 rotary into reverse rotary motion has been proposed, and that in some respects this resembles the mechanism shown in Figs. 11 and 12; but my mechanism is constructed and arranged to convert an oscillating motion of 40 forty-five degrees into an oscillating motion

somewhat in excess of one hundred and eighty degrees.

Having thus described my invention, I claim—

1. The combination of the cup-like shuttle 45 *A*, provided with a recess, *b*, and spindle *e*, the thread-guide *B*, provided with a tubular spindle, *f*, with spring *i*, a thread-tension spring, and a spring, *o'*, to press against the shuttle-wall, and the bobbin *C*, all substantially as set forth.

2. In a sewing-machine, the combination, 55 with the needle-plate of a sewing-machine provided with a shoulder, *m*, of the cup-like shuttle *A*, provided with a recess, *b*, the thread-guide *B*, provided with a tension-spring, *n*, and its slide *g*, and a shoulder, *l*, to catch against the shoulder on the needle-plate, and mechanism, substantially as described, for imparting an oscillating movement to the shuttle, as described.

3. As a means for imparting an oscillatory movement to the shuttle of a sewing-machine, the combination of the shaft *s*, crank *t*, connecting-rod *v*, guide-block *w*, radially-mounted rod *x*, block *y*, and shuttle-bearing disk *y'*, provided with a shuttle-driving pin, *w'*, all arranged to operate substantially as set forth.

4. The combination, with a detached cup-like shuttle for a sewing-machine, of the thread-guide *B*, provided with a vertical side or wall, *h*, a tension-spring, *n*, arranged in an opening in said wall, a ratchet, *r'*, a slide, *q*, and a spring, *r*, to engage the ratchet, all substantially as herein set forth.

FERDINAND OTTO SCHMIDT.
